UNITED STATES PATENT OFFICE

WILLIAM J. BAKER, OF NEWPORT, AND HARRY A. KONEN, OF CLIFTON, KENTUCKY,
ASSIGNORS TO W. J. BAKER COMPANY, OF NEWPORT, KENTUCKY, A CORPORATION
OF KENTUCKY

ROLL-SCREEN HOLDING DEVICE

Application filed January 21, 1930. Serial No. 422,326.

This invention relates to a releasable stop or catch mechanism for retaining in a lowered position an object, such as a spring roll screen, which is normally urged in an upward direction.

5 An object of the invention is to provide stop means of the class described which become automatically operative upon downward movement of the device with which 10 the stop mechanism cooperates.

Another object is the elimination of hooks, clamps, and the like for retaining a device of the class described in its lowered position.

Another object is the provision of a stop 15 mechanism which is positive in its action and simple in construction and operation.

These and other objects are attained by the means described herein and set forth in the accompanying drawing, in which:

20 Fig. 1 is a rear elevational view of a conventional window frame with a roll screen embodying the device of this invention;

Fig. 2 is an enlarged view taken on line 2—2 of Fig. 1;

25 Fig. 3 is an enlarged view taken on line 3—3 of Fig. 1;

Fig. 4 is a detail view of a part of the device, parts being broken away;

Fig. 5 is a view taken on line 5—5 of Fig. 4;

30 Fig. 6 is an edge view of a nut forming a detail of the invention.

The device of this invention is particularly useful in connection with roll screens and is set forth herein as applied to such a screen.

35 The stop mechanism is adapted to cooperate with both sides of a screen. Inasmuch as the structure is the same on each, the device will be explained as applied to one side only.

The window frame 6 may comprise a casing 7 housing a spring-actuated roll (not shown) to which screening 8 is attached. The screening 8 is normally urged by the spring-actuated roll to an upward or rolled-up, non-operative position. Two strips 9 and 10 are secured in spaced, parallel relationship, to the opposed or inner faces of the sides of the window frame 6. Screen guides 11, extending from the top to the bottom of the frame 6, are positioned in the space 12 between strips 9 and 10. Guides 11 consist of

strips, preferably of metal, joined, as at 13, along one longitudinal edge, and having the free portions thereof bent substantially into L shape so as to provide the spaced, parallel walls 14 and 15, having rolled edges 16 ex-

55 tends outwardly beyond the inner side faces of the window frame 6 to a slightly greater extent than the strips 9 and 10. The joined edge portions of guides 11 are positioned and secured beneath the strip 9. It is

not essential that guides 11 be positioned between strips, such as 9 and 10. The guides may be attached directly to the exposed side faces of a window without affecting the operation of the device, thus facilitating installation of the screen in windows originally un-

60 equipped with the strips 9 and 10. Walls 14 and 15 serve as guideways for the side edges of screening 8. A strip of spring metal 17, curved inwardly of guide 11, is disposed longitudinally against the inner face of wall 14, adjacent the lower end thereof, being secured thereto by its upper end only, which seats in a depression 18 in the wall 14.

65 At a point substantially opposite the mid-portion of the positioned spring 17, a section of wall 15 is extruded to form a longitudinally extending rib 27. Rib 27 is slotted longitudinally to receive the shank of a threaded bolt 28 adapted to be screwed into a nut 29

70 seated non-revolubly in the interior depression formed by rib 27. Nut 29 is beveled or tapered along its uppermost-edge portion as indicated at 290, Figs. 2 and 6. It is obvious that the bolt and nut may be slidably moved to 75 adjusted positions along the slotted rib 27.

75 The lower edge of screening 8 is suitably secured to the rigid, movable bottom strip or bar 19. The ends of strip 19 project into the guides 11, and are provided with bosses or ridges 23 adapted to abut the turned-in portion of one of the edges 16 to prevent withdrawal of the positioned strip 19. Flanges 21 and 22 on strip 19 may be provided for facilitating movement of the screen. When the screen is drawn down to its lowered position, the ends of strip 19 pass readily over nut 29 by reason of the bevel 290 thereon. After passing beneath the nut 29 the strip 80 ends are urged by spring 17 against the inner

faces of walls 15 whereupon the tops of ridges 23 come into abutment against the underside of the nuts 29 which serve as stops. The screen is thus prevented from rising until the 5 ends of strip 19 are again pressed against spring 17 whereby ridges 23 are permitted to pass upwardly beyond the retaining nuts 29. It should be noted that the ends of strip 19, in the lowermost position of the screen, 10 do not pass entirely beneath the lower or free end of the spring, so that obstruction of or interference between these parts in moving the screen, is avoided. A fabric strip 25 may be attached to the under side of flange 22 to prevent 15 scratching or marring of the window sill 26.

The above structure may be slightly modified by omitting the spring 17. In this case the normal inclination of bar 19 in the direction 20 of guide wall 15, which inclination results from the upward pull of screening 8 on one side of bar 19, is utilized for holding ridges 23 in contact with the under edges of nuts or stops 29. The manual turning of bar 25 19 upon its longitudinal axis, in the opposite direction serves to bring ridges 23 clear of the one way stops 29, whereupon the screen may be raised.

It may happen in some instances, that the 30 guides 11 are not quite long enough to abut the window sill at their lower ends. In order to close the opening between the screen and the sill that would otherwise result in such an instance, the bolt 28 may be adjusted 35 downwardly of the slotted rib 27 whereby nuts 29 retain the strip 19 in such position that the strip bottom will contact the sill.

What is claimed is:

1. In combination, an upwardly-urged 40 screen and a guideway therefor, a strip attached to the bottom edge of the screen and having an end extending into the guideway, a lateral projection on said end of the strip and adapted to preclude withdrawal of the 45 positioned strip from its guideway, a spring in the guideway adjacent the lower end thereof and normally urging said lateral projection against a wall of the guideway, and abutment means disposed in the guideway adjacent the spring and movable to adjusted position relative to the end of the guideway, said abutment means being adapted to prevent movement of the spring-urged strip end past the abutment until the application of pressure 55 upon the strip overcomes the action of said spring.

2. In combination an upwardly-urged 60 screen and a guideway therefor, a strip attached to the bottom edge of the screen and having an end projecting into the guideway, a boss on the end of said strip and adapted to preclude withdrawal of the positioned strip from its guideway, spring means in the 65 guideway for urging said boss against an inner face of its guideway when the screen is

in its lowered position, and an abutment in the guideway upon said inner face and movable longitudinally of the guideway to adjusted positions relative to the end of the guideway, said abutment being beveled on its 70 upper side to permit downward movement of the boss past the abutment and squared on its lowest side to prevent return movement thereof by the upwardly-urging force normally operative upon the screen. 75

3. The combination with an upwardly-urged screen and a guideway therefor, of a bottom strip attached to the lower edge of the screen and having an end extending into the guideway, an adjustable abutment in said 80 guideway adjacent the bottom thereof and disposed above the strip end in the lowered position of the screen, and a projection on said strip end extending at substantially right angles therewith and adapted to be held by the upward force normally operative on the screen in contact with said abutment when the screen is in its lowered position, movement of the strip on its longitudinal axis serving to permit passage of the projection past the 85 abutment, said projection being adapted to preclude withdrawal of the strip end from their guideway. 90

4. The combination with an upwardly-urged screen and a guideway therefor, of a 95 bottom strip attached to the lower edge of the screen and having an end extending into the guideway, an abutment in the guideway, and a boss on the strip end adapted when disposed beneath the abutment to be held in contact 100 therewith by the upward force normally operative upon the screen, said boss being adapted to preclude withdrawal of the strip end from the guideway.

In testimony whereof, we have hereunto 105 subscribed our names this 14th day of January, 1930.
